US0D1005235S

(12) **United States Design Patent** (10) **Patent No.:** **US D1,005,235 S**
(45) **Date of Patent:** **** Nov. 21, 2023**

(54) **3 IN1 MAGNETIC WIRELESS POWER BANK**

(71) Applicant: **Shenzhen Sujue Electronic Technology Co., LTD**, Shenzhen (CN)

(72) Inventor: **Liangliang Su**, Shenzhen (CN)

(73) Assignee: **Shenzhen Sujue Electronic Technology Co., LTD**, Shenzhen (CN)

(**) Term: **15 Years**

(21) Appl. No.: **29/897,149**

(22) Filed: **Jul. 12, 2023**

(51) LOC (14) Cl. **13-02**

(52) U.S. Cl.

USPC **D13/108**

(58) **Field of Classification Search**

USPC D13/108, 103, 107, 118

CPC Y02E 60/10

(57) **CLAIM**

The ornamental design for a 3 in1 magnetic wireless power bank, as shown and described.

DESCRIPTION

FIG. 1 is a front perspective view of a 3 in1 magnetic wireless power bank showing my new design;

FIG. 2 is a rear perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate the portions of the 3 in1 magnetic wireless power bank, which form no part of the claimed design.
